EASEL

Filed July 3, 1928

INVENTOR

EDWARD M. ROBERTS
by *Munn & Co* ATTORNEYS

UNITED STATES PATENT OFFICE

EDWARD M. ROBERTS, OF LONG BEACH, CALIFORNIA

EASEL

Application filed July 3, 1928. Serial No. 290,069.

My invention relates to easels, and it has for a purpose the provision of an easel of relatively simple, inexpensive, and durable construction, and which is capable of holding and displaying relatively thin objects such as pictures, paintings, and photographs, and relatively thick objects such as books.

I will describe only one form of easel embodying my invention and will then point out the novel features in claims.

In the accompanying drawing:

Figures 1 and 2 are views showing in perspective one form of easel embodying my invention, the ledge member being removed from Fig. 1 to show another adaptation of my invention.

Referring specifically to the drawings, my invention in its present embodiment comprises an inverted U-shaped frame constructed of two strips of metal or other suitable material having linear portions 15 secured by rivets 16 to each other and in spaced parallel relation. From the lower ends of the linear portions 15 reversely curved portions 17 extend and merge into flat diverging portions 18 disposed at right angles to the curved portions by twisting the metal at the junction of the two, as indicated at 19.

The lower ends of the diverging portions 18 are bent to form brackets 20 of L form and with the vertical portions of the brackets slightly spaced from the diverging portions 18 and the substantially horizontal portions of the brackets projecting forwardly and at right angles to the diverging portions 18.

The upper ends of the linear portions 15 are bent outwardly and substantially at right angles to provide lateral extensions 21, the linear portions and extensions coacting to form a T-shaped head for the U-shaped frame. This head, in so far as the functioning of the frame to support a picture or other article thereon, is a continuation thereof in that it does assist in supporting a picture or other article should it be longer than

the frame. Further, the head constitutes a handle to be gripped in moving the easel from place to place as will be understood.

For supporting the frame and its head in inclined position in the usual manner of easels, I provide a leg 22, also formed from a strip of metal or other suitable material and which, by means of the lower rivet 16, is pivotally mounted at its upper end between the link portions 15 in order that it may be movable to occupy various positions to support the frame at any desired inclination. The linear portions are associated with the upper end of the leg 22 in such manner that they operate to frictionally retain the leg 22 in any adjusted position. In order that the lower end of the leg may have proper contact with any support upon which the easel is placed and in a manner to prevent rearward swinging movement of the leg, and, as a consequence, collapsing of the frame, the strip of which the leg is formed is twisted intermediate its ends, as indicated at 23, thereby disposing that portion of the leg beneath the twist at right angles to that portion of the leg above the twist and, as a consequence, disposing the lower end of the leg at right angles to the pivot 16.

For the purpose of supporting relatively thick objects such as books and the like, I provide a ledge member comprising a flat body portion 24 and a depending lip 25, the two being made from a single sheet of metal or other suitable material. In its association with the frame, the lip 25 of the ledge member is inserted between the vertical portions of the brackets 20 and the diverging portions 18, the body 24 of the member reposing on the horizontal portions of the brackets, all as illustrated in Fig. 2. With the ledge member applied as described, it forms a bridge between the brackets 20 and a ledge of such width as to provide ample support for books or other objects of various thickness. In dotted lines I have illustrated, in Fig. 2, an

open book in applied position on the easel, its lower edge reposing on the ledge member and its back resting against the frame of the easel.

5 In Fig. 1 the ledge member has been removed, and in dotted lines I have shown a picture and its frame in applied position on the easel. As applied, the lower edge of the frame of the picture reposes on the horizontal portions of the brackets, the back of the frame resting against the frame of the easel and also on the linear portions 15 of the head. It will be understood that if the picture frame is of such height as to extend beyond the frame, the T head will function to support the upper part of the frame. It will, of course, be understood that the bridge member is removable from the brackets when not in use, and that the leg 22 can be folded to a 10 position within the frame of the easel to facilitate packing and shipment.

15 Although I have herein shown and described only one form of easel embodying my invention, it is to be understood that various 20 changes and modifications may be made herein without departing from the spirit of the invention and the spirit and scope of the appended claims.

I claim:

20 1. An easel comprising two strips of material having linear portions secured to each other, reversely curved portions extending from the linear portions, flat diverging portions at right angles to the curved portions, 25 the free ends of the diverging portions terminating in brackets having extensions outwardly projecting from the diverging portions, a supporting leg pivoted between the linear portions and frictionally embraced by the latter to maintain the leg in any position of adjustment, and a ledge member bridging the brackets and having a lip engaging within the brackets, and a body portion supported on the extensions.

30 45 2. An easel comprising two strips of material having linear portions secured to each other, reversely curved portions extending from the linear portions, flat diverging portions at right angles to the curved portions, 50 the free ends of the diverging portions terminating in brackets having extensions outwardly projecting from the diverging portions, portions extending laterally from the upper ends of the linear portions, a supporting leg pivoted between the linear portions and frictionally embraced by the latter to maintain the leg in any position of adjustment, and a ledge member bridging the brackets, and having a lip engaging within the 55 brackets, and a body portion supported on the extensions.

3. An easel comprising an inverted 60 U-shaped frame having L-shaped brackets at the lower ends thereof, and a ledge member 65 having a lip received between the brackets

and the frame and the body of the ledge member supported on the brackets.

4. An easel comprising an inverted U-shaped frame having L-shaped brackets at the lower ends thereof, and a ledge member of L-shape in cross section having one portion received between the frame and brackets and the other portions supported on the brackets.

Signed at Long Beach, in the county of Los Angeles and State of California this 21st day of June, 1928.

EDWARD M. ROBERTS.
